TAPE DECK

Terrance N. Taylor, Palatine, Ill., assignor to Ampex Corporation, Redwood City, Calif., a corporation of California

Filed Dec. 17, 1969, Ser. No. 20,542

Term of patent 14 years

Int. Cl. D14—01

U.S. Cl. D26—14

The figure is a perspective view of the top, back, and left side of a tape deck showing my new design, the right side being a mirror image of the left side, the front being a continuation of the adjacent portions of the sides, and the bottom being conventionally plain.

I claim:

The ornamental design for a tape deck, substantially as shown and described.
